UNITED STATES PATENT OFFICE.

JOHN DENTON, OF PATERSON, NEW JERSEY.

FLUSH-TANK VALVE.

SPECIFICATION forming part of Letters Patent No. 681,302, dated August 27, 1901.

Application filed December 31, 1900. Serial No. 41,581. (No model.)

To all whom it may concern:

Be it known that I, JOHN DENTON, a citizen of the United States, residing in Paterson, county of Passaic, and State of New Jersey, 5 have invented new and useful Improvements in Flush-Tank Valves; and I do hereby declare the following to be a full, clear, and exact description of the invention, such as will enable others skilled in the art to which it 10 appertains to make and use the same, reference being had to the accompanying drawings, and to characters of reference marked thereon, which form a part of this specification.

15 This invention relates to flushing apparatus for water-closets, and it has reference particularly to the construction of the supply-valve of such an apparatus.

The invention consists in the improved supply-valve for a flushing apparatus for water-closets and in the combination and arrangements of its various parts, substantially as will be hereinafter pointed out, and finally embodied in the clauses of the claim.

25 Referring to the accompanying drawings, wherein the invention is fully illustrated, Figure 1 is a view of a flushing apparatus provided with my improved supply-valve. Fig. 2 is an enlarged vertical sectional view 30 of the supply-valve. Fig. 3 is a vertical sectional view of a modified form of the supply-valve, and Fig. 4 illustrates a detail of the valve.

In the drawings, *a* designates a tank of any 35 suitable construction, and *b* and *c* denote the supply and discharge pipes. In the discharge-pipe is located a valve-casing *d*, having a valve *e*, which controls the flow from the tank through said pipe and which is 40 adapted to be actuated by a lever *f*, having the usual chain *g* and connected with the valve by a valve-stem *h*.

i designates the valve-casing for the supply-pipe. This casing comprises a chamber 45 portion *j* and a tubular portion *k*, preferably integrally formed and having a communicating port *l*. To one end of the tubular portion *k* is adapted to be attached, by a suitable coupling *m*, the supply-pipe *b*. The chamber 50 portion *j* is provided with aligned and threaded openings *n o*. One of these is fitted with a threaded plug *p*, while the other, *o*, receives

the threaded end of a tubular thimble *q*, which penetrates the bottom wall of the tank and is provided with an enlargement *r* at its 55 upper end, which when the thimble is screwed tightly into place in the valve-casing coats with the casing in binding said wall between them, and thus producing a tight joint. A washer *s* may be interposed between the enlargement and said wall. A washer *t* may likewise be interposed between the casing and said wall, the former being, as best shown in Fig. 2, provided with an annular groove *u*, formed about the threaded opening *o* and 60 adapted to receive said washer. The enlargement *r* is provided with a discharge-opening *v*, and its upper end is covered by a cap *w*, which is preferably screwed into place and carries an arm *x*, upon which is 65 fulcrumed a short lever *y*, adapted to receive the end of a stem *z* for a float 2.

The lower end of the thimble *q* forms a port of communication between the valve-casing and the body portion of said thimble, 75 and it is adapted to be controlled by a plug *3*, which seats against the end of the thimble, being carried by a valve-stem *4*, which penetrates the thimble and protrudes through its cap, its head *5* having an opening *6*, through 80 which the lever *y* extends. In order to guide the valve-stem and, thus insure the proper seating of the valve, the former may be extended, as seen in Fig. 2, so as to project into the bore 7 of an integral nipple *8*, formed 85 on the plug *p*. The extended portion, for a reason hereinafter explained, is shown in the drawings as made separable from the body portion of the stem; but it is to be understood that it may be made integral therewith. 90

In order to secure the valve-casing against turning on the thimble, it may be secured by screws or other devices 9.

In the modification of my invention shown 95 in Fig. 3 a somewhat cheaper construction is produced, an ordinary $\frac{1}{10}$ being used for the valve-casing. This figure also illustrates that solder may be employed to insure a tight joint on the inside of the tank around the 100 thimble, as at 10'.

The plug or valve *3* is preferably secured on the valve-stem *4* by an adjusting-screw *11*, which is tapped into the end of the valve-

stem, this end taking against a washer 12, between which and another washer 13 on the valve-stem the valve is compressed. The end of the valve-stem is reduced, thus forming a shoulder 14, against which the washer 13 abuts. This construction permits the adjustment of the shape of the plug or valve, it thus being capable of being altered to fit the particular valve-seat to which it is applied, it being remarked that said valve is made of elastic rubber. The separable plug *p* permits access to the interior of the valve-casing *i*, either for cleaning the same or adjusting or replacing the valve 3. In order to perfectly insure the seating of the valve 3, as when pressure in pipe *b* is high, a spiral spring 15 may be interposed between the bottom of the valve and the plug *p*, said spring receiving at its upper end the end of the valve-stem. Having thus fully described my invention, what I claim as new, and desire to secure by Letters Patent, is—

1. In a flushing apparatus, the combination of a tank, a supply-pipe, a hollow thimble penetrating one of the walls of said tank and having an apertured enlargement adapted to take against one side of said wall, a valve-casing screwed onto the other end of said thimble and adapted to engage the other side of said wall, said pipe being connected with said valve-casing, a plug removably secured in said valve-casing in alinement with the thimble, a valve-stem penetrating said thimble,

and a valve controlling the communication between the thimble and the valve-casing and disposed on the end of said valve-stem which is inclosed by the casing, substantially as described.

2. In a flushing apparatus, the combination of a tank, a supply-pipe, a hollow thimble penetrating one of the walls of said tank and having an apertured enlargement adapted to take against one side of said wall, a valve-casing screwed on the other end of said thimble and adapted to engage the other side of said wall, said pipe being connected with said valve-casing, a plug removably secured in said valve-casing in alinement with the thimble, a valve-stem penetrating said thimble, an elastic valve controlling communication between the thimble and the valve-casing and disposed on the end of said valve-stem which is inclosed by the casing, said valve-stem having an abutment against which the valve takes, and a headed screw tapped into said end of the valve-stem and adapted for adjusting the valve, said screw being guided in the plug, substantially as described.

In testimony that I claim the foregoing I have hereunto set my hand this 17th day of December, 1900.

JOHN DENTON.
